DUPLEX STEAM MOTOR

George E. Campbell, Chattanooga, Tenn., assignor
to The Wheland Company, Chattanooga, Tenn.,
a corporation of Tennessee

Application August 10, 1936, Serial No. 95,291

1 Claim. (Cl. 121—114)

This invention relates to an improvement in duplex steam motors, and is more particularly directed to the steam end of a direct-acting duplex steam pump.

In my former patent, No. 2,037,697, granted April 21, 1936, on Duplex steam motors, provision was made for the location of the exhaust valves for the motor below the cylinders in order to drain condensation from the cylinders through the exhaust valves. However, the intake valves were above the cylinders, separate from the exhaust valves, which required more mechanism to build than if these were unitary.

The object of the present invention is to simplify the construction of the motor, reducing the number of moving parts, and providing a cheaper construction than that set forth in my prior patent, while at the same time obtaining the advantage of draining condensation from the cylinders through the valves.

This is accomplished by the provision of one valve for each cylinder, so constructed that it will control the admission and exhaust of steam from the cylinder, and will be located adjacent the bottom of the cylinder so that any water of condensation occurring in the cylinder will flow freely by gravity from the cylinder through the valve, thus providing a self-draining engine or steam end of a duplex pump.

The difference between a steam cylinder for an ordinary steam engine and a steam cylinder for a direct-acting steam pump is that in the steam engine the live-steam ports and the exhaust-steam ports may be the same, whereas in a steam pump it is customary to use four steam ports for each cylinder; the two ports nearest the extreme ends of the cylinder are used for the admission of steam, while the two ports spaced from the ends are used for the exhaust. The reason for this is that the piston is stopped at each end of its stroke by the steam action or compression occurring after the piston passes over and closes the exhaust port.

When the motor is stopped, the steam trapped in the cylinder condenses and forms water therein, which may be increased by leakage of valves. Upon starting up the motor, this water which has accumulated in the cylinder is objectionable and very often causes breaking of cylinder-heads when the piston comes back thereagainst with considerable force. By locating the valves below the cylinders and by having the passageways extend upwardly to the cylinders from the valve chest, the opening of the valves immediately causes the water to be drained from the cylinders, so as to prevent damage to the cylinder heads,

and also prevent interference with the proper operation of the pump.

A preferred embodiment of this invention is illustrated in the accompanying drawings, in which:

Fig. 1 is a side elevation, partly in section, through a duplex steam pump;

Fig. 2 is a top plan view of the steam end of the pump;

Fig. 3 is an end elevation thereof;

Fig. 4 is a vertical transverse sectional view through the steam end substantially through the mid-portion thereof;

Fig. 5 is a detail transverse sectional view through one of the valves, at the point of admission;

Fig. 6 is a longitudinal sectional view through one of the valve sleeves removed, showing the valve therein and partly in elevation;

Fig. 7 is a rear elevation of the lever mechanism for operating the valves and Fig. 8 is a transverse vertical section on the line 8—8 of Fig. 2, the left-hand end of the line being through the steam end, and the right-hand end of the line through the exhaust of the pump.

The invention is shown as applied to a duplex steam pump designated P in Fig. 1, while the steam end of this pump which forms the subject-matter of this invention is designated E.

This steam end of the pump comprises a pair of parallel steam cylinders 1 and 2, in which are mounted pistons 3 and 4, respectively, connected directly with connecting-rods 5 and 6, which connecting-rods operate through a cradle 7 and extend to the usual pump pistons located in the pump end of the duplex steam pump.

A valve chest 8 is formed in the lower portion of the steam end below the cylinders 1 and 2, and is provided with intake and exhaust chambers 9 and 10, respectively, each of which communicates with both cylinders. Passageways 11 extend upwardly to opposite ends of each cylinder and form the intake passageways, while passageways 12 are spaced inwardly slightly from the passageways 11 and form the exhaust passageways. The exhaust passageways 12 are spaced inwardly from the ends of the cylinder further than the passageways 11 in order to trap some of the steam in the end of the cylinder to act as a cushion for the piston, particularly when the invention is used in connection with a duplex steam pump where this action is desired.

Mounted in valve openings 13 in the valve chest 8 are sleeves 14 having openings c arranged therein for communicating at opposite ends with

the intake steam chamber 9 and at an intermediate point with the exhaust steam chamber 10. Communication through the sleeve 14 with the respective passageways and chambers is controlled by valves 15 and 16 for the cylinders 1 and 2, respectively. The valves 15 and 16 are of the usual balanced piston type, and are connected, respectively, with valve-stems 17 and 18, on which the piston-valves are fixed against lost motion. However, there is lap on the valves for properly timing the admission and exhaust of steam.

The valve-stems 17 and 18 are operated by the usual cross-over lever arrangement, except that it is inverted and secured beneath the cradle 7. In this position, the supporting stand 19 is fixed to the under side of the cradle and has cross-shafts 20 and 21 journaled therein, as shown in Fig. 7. The shaft 20 has at one end a lever 21' carrying a roller 22, which operates within a spool 23 fixed to the connecting rod 5. The opposite end of the shaft 20 has a rocker-arm 24 fixed thereto and connected with the valve-stem 18. The other cross-shaft 21 carries an upstanding lever 25 with a roller 26 operating in a spool 27 fixed on the connecting-rod 6. The opposite end of the shaft 21 has a rocker-arm 28 thereon connected with valve-stem 17. Thus the piston 3 reciprocates its connecting-rod 5 to operate lever 21', shaft 20, rocker-arm 24, and the valve-stem 18 for the other cylinder, which encloses the piston 4. In turn, the piston 4 controls the valve for the cylinder 1 through the cross-over arrangement described so that the piston of one of the duplex cylinders operates the valve of the other cylinder.

The valve chest may be provided with suitable steam inlet and exhaust openings, the former of which may be in the top or the side, and the latter in either side or bottom. The steam inlet is shown at 29 between the cylinders for supplying steam to the steam chamber 9 the steam on entering flowing beneath the walls *b* in opposite directions, while the exhaust is shown at 30 in the bot-

tom of the chamber 10, although provision is made for exhausting steam through either of the lateral outlets 31 or 32 upon the removal of the respective cap therefor.

Thus it will be seen that the live steam enters 5 at a point above the exhaust, and the condensation passes out through the bottom of the pump, by gravity, its passage only being impeded by the valves in the lower portion of the pump.

The provision of a single combined intake 10 and exhaust valve for each cylinder simplifies the construction and operation, and cheapens the manufacture, and yet by locating the combined intake and exhaust valve below the cylinder it will control the admission and exhaust 15 of steam and will be located in such position that any water of condensation which may occur in the cylinder will flow downwardly through the passageways by gravity and be exhausted from the cylinder, thus providing a self-draining steam 20 end in a duplex pump, of simple construction and operation.

I claim:

The combination of steam cylinders, valve chests extending parallel therewith, separate un- 25 obstructed passageways for the admission and exhaust of steam leading downwardly from the cylinders and into the valve chests therebeneath, piston valves located in the valve chests, a steam intake chamber located between and below the 30 cylinders and extending downwardly and branching toward each end of the cylinders and connecting with the outer ends of the valve chests, a chamber for the exhaust steam connecting the valve chests and provided with a suitable out- 35 let below the valve chests, the combined steam and exhaust chambers being so located and ar- ranged that the valves present the only obstruc- 40 tion to the free flow downwardly by gravity of the condensation to the exhaust and away from the pump without entering the cylinders, and means for operating the valves.

GEORGE E. CAMPBELL.
